UNITED STATES PATENT OFFICE

152,545

DESIGN FOR A RADIATOR CABINET OR
THE LIKE

Joseph Israel, New York, N. Y.

Application November 20, 1946, Serial No. 134,943

Term of patent 3½ years

(Cl. D81—21)

To all whom it may concern:

Be it known that I, Joseph Israel, a citizen of the United States, and a resident of New York city, in the county of Queens and State of New York, have invented a new, original, and ornamental Design for a Radiator Cabinet or the Like, of which the following is a specification, reference being had to the accompanying drawing, forming part thereof, in which:

Figure 1 is a front elevation of a radiator cabinet or the like, embodying my design.

Figure 2 is a side elevation thereof.

Figure 3 is a top view thereof.

Figure 4 is a rear elevation.

The grill, which is only partly shown, extends throughout the dotted line areas.

I claim:

The ornamental design for a radiator cabinet or the like, as shown and described.

JOSEPH ISRAEL.
